UNITED STATES PATENT OFFICE.

JOHN HEWITSON AND ELIJAH TOLMAN, OF TAUNTON, MASSACHUSETTS,
ASSIGNORS TO REED & BARTON, OF SAME PLACE.

MACHINE FOR ORNAMENTING METAL SURFACES.

SPECIFICATION forming part of Letters Patent No. 225,829, dated March 23, 1880.

Application filed September 20, 1879.

To all whom it may concern:

Be it known that we, JOHN HEWITSON and ELIJAH TOLMAN, of Taunton, in the county of Bristol and State of Massachusetts, have invented a new and Improved Machine for Ornamenting Metal Surfaces; and we do hereby declare that the following is a full, clear, and exact description of the same, reference being had to the accompanying drawings, forming part of this specification.

This invention consists of a machine for producing all kinds of chased or matted surfaces, but more particularly for producing an improved finish, which we call the "snow-flake" finish.

It consists in the peculiar construction and arrangement of mechanism for imparting a combined rotary and impacting movement to a tool, and also in the peculiar construction of the face of the tool, as hereinafter fully described.

Figure 1 of the drawings is a side elevation, partly in section, and Fig. 2 a plan view, of the machine. Fig. 3 is a side view of the finishing-tool for producing the snow-flake finish. Fig. 4 is an enlarged face view of the same.

In said drawings, A represents a frame-work, in which is mounted, in suitable bearings, a horizontal shaft, B, which shaft is driven by a fixed pulley, C, having a loose companion pulley, C', by its side. Upon this shaft is fixed a six-pointed cam, D. Pivoted to the frame-work, at its back end, is a hammer, E, which is alternately lifted and allowed to fall by the action of the cam upon the spring F and roller a, arranged between the hammer and the cam. To secure a positive and elastic blow this hammer is drawn downwardly by a spring, G.

H is an arm fixed to a standard rising from the base-frame, which arm carries at its outer end a stationary sleeve, b, in which revolves the vertical tool c, located directly beneath the face of the hammer, and in such proximity to the same as to be struck by each descent of the hammer.

This tool for giving the snow-flake finish has a working-face composed of fine parallel ridges and center-punch indentations, as shown in Fig. 4, and is rotated by a belt, g, passing around a pulley, d, on the tool, and also around

a pulley, e, on the drive-shaft, and is held up 50 by a spiral spring, f, arranged in the lower end of the sleeve b.

The lower end of the tool is the operating-face, which, it will be seen, intermittently advances against the surface to be finished with 55 an impact derived from the blow of the hammer, having meanwhile a rotary motion about its axis from the action of the belt. The sudden impact of the tool against the surface to be finished causes a set of parallel indentations 60 on the metal surface, which appear in patches, with the parallel lines of one patch appearing at a different angle to those of the next. As the time of contact between the tool and surface to be finished is only momentary, the parallel lines are not obliterated by the rotary action, the latter serving only to place the patches in different angular relation on the metal surface.

In operating upon the article, the latter, as 70 shown at X, is preferably held upon a handle, I, which latter is suspended from a pulley above by a rope or cord, J, by pulling upon which, either by the hand or by a treadle, the object is brought up to the operating-tool, while said 75 object may be turned to present new surfaces by means of the handle I.

In making use of the peculiar organization of machine for imparting motion to the tool we do not confine the same to its use with the peculiar form of tool described, nor do we confine ourselves in the use of this peculiar construction of tool to the mechanism here shown for operating it.

In defining our invention more clearly we 85 would state that we are aware that a tool for ornamenting metal has heretofore been constructed to act with a combined rotary movement and endwise impact; but in such case the endwise reciprocation was effected by a 90 cam and spring within the tube containing the tool and operating on the principle of a dental plunger. Such construction, however, does not afford the sudden and elastic blow which is required to give the desired finish, nor a sufficient means for adjusting the strength of said blow, as when the hammer is arranged exteriorly for endwise impact.

We are aware, also, that a tool having a face of parallel hair-lines is not new, and we do not claim the same, except when the lines are broken up by the center-punch indentations, which have the effect to break up the continuity of the lines produced on the indented surface of metal being ornamented, and, by breaking up the continuity of the lines of light reflected therefrom, give a more ornamental design.

With respect to the design formed by the use of the tool herein described, we do not claim this jointly in this application, as the same has been covered by John Hewitson singly in an application for a design patent filed January 3, 1880.

Having thus described our invention, what we claim as new is—

1. The combination, with the tool having a free rotary and longitudinal movement, of the belt *g* and pulley *e*, and the cam *D*, and horizontal spring-actuated hammer *E*, having its face in line with the axis of the tool, substantially as shown and described.
2. The tool having a face wrought into fine parallel ridges dotted with center-punch indentations, as shown and described.

JOHN HEWITSON.
ELIJAH TOLMAN.
